UNITED STATES PATENT OFFICE

LOUIS M. NESSELBUSH, OF YOUNGSTOWN, OHIO, ASSIGNOR TO THE FALCON BRONZE COMPANY, OF YOUNGSTOWN, OHIO, A CORPORATION OF OHIO

TUYÈRE

Application filed July 17, 1929. Serial No. 378,827.

This invention relates to improvements in blast furnace tuyères, mantle and Bosh plates or other devices of similar character or forms of ports which are subjected to high temperatures or are liable to be splashed by molten metal in use.

The present invention however, is illustrated as embodied in a blast furnace tuyère but it is to be understood that the term tuyère as hereinafter appearing in this specification and in the claims, is to be understood to include in its meaning, any and all of the above described devices to which this invention has application.

15 It is an object of this invention to provide tuyères of improved character having a nose portion protected with refractory material, all of such construction that a relatively cheap, yet highly efficient device is provided 20 and one which has a longer life and gives greater satisfaction and use than tuyères heretofore devised.

A further object of this invention is to provide a tuyère, the refractory nose of 25 which is covered with an outer protecting metal shell and is provided with metallic web portions extending between the outer protecting shell and a wall of the water compartment, whereby to convey heat rapidly 30 from the outer shell in a manner to cool the outer shell and prevent damage thereto.

A further object is to provide a tuyère 35 which has refractory material covering the ends of the water compartment, and also covering the sides of the water compartment throughout that portion of the length thereof which is subjected to the most severe damage, to provide openings in the side of the 40 tuyère at locations intermediate the length thereof and removed from the nose portion, through which refractory material may be introduced into the compartments or space provided therefor.

45 Another object of this invention is to provide a tuyère having a protective covering of refractory material and a metallic protecting wall for said refractory material in which the refractory material is contained 50 in small compartments separated by walls

which serve to hold the refractory material in place, even though the outer wall has become completely worn away and which also serve to rapidly conduct the damaging heat at the outer surface of the nose portion 55 of the tuyère to the water compartment.

It is a further object of this invention to provide a tuyère, the entire variation in length of which is relatively small, as compared with other known types of tuyères, 60 having noses protected with refractory material whereby a better and more accurate control of the wind penetration is realized.

It is known in the use of blast furnaces that the degree of penetration of the wind 65 introduced therein depends upon the length of the tuyère and accordingly it is desirable to have a tuyère, the over-all length of which will not be reduced to any material extent in use, as variations in length make 70 for different and uncontrolled degrees of wind penetration.

The present invention therefore, provides a construction whereby the tuyère is shortened in over-all length, a minimum amount 75 occasioned by deterioration and wearing away, in use.

Another object of this invention is to provide a tuyère which increases the value of the cooling chamber of the tuyère as 80 means are provided for conducting the heat from the outer surface of the nose portion into the cooling chamber.

A further object of this invention is to provide a tuyère which offers a maximum resistance to wear as well as heat. The ordinary standard tuyères now in use are relatively resistant to wear but are subject to being readily burned out, whereas refractory nose tuyères are quite resistant to heat 90 but do not embody a maximum resistance to wear. The present invention aims to combine both of these good qualities.

A further object of this invention is to provide a tuyère which has an unusually 95 long life and yet is relatively cheap to manufacture, and will resist, to a maximum degree, deterioration and wearing away, under the exposure to heat and friction occasioned in use and yet even though the outer protect- 100

ing metal shell becomes worn away, is one which provides a completely operative and relatively durable tuyère, capable of a further relatively long period of use.

5 Various other objects not specifically enumerated herein, are accomplished by this invention as will readily appear to one skilled in the art as the description herein-after given proceeds.

10 It is to be understood that the following detailed description covers merely one preferred form of the present invention and is given by way of illustration and is not to be considered as limiting the invention in any respect.

15 The full scope of the invention may be determined from an understanding of the present illustrative embodiment thereof and an appreciation of the advantages which the 20 present invention produces therein.

The following disclosure will be more readily understood by referring to the accompanying drawings in which—

Figure 1 is a longitudinal cross sectional view taken on the line 1—1 of Figure 2, and constructed in accordance with the present invention.

Figure 2 is a transverse cross sectional view taken on the line 2—2 of Figure 1.

20 By referring to the drawings, it will be noted that the present invention is illustrated as embodied in a tuyère 10, of the usual hollow annular construction, having the wind passage 11 and the water compartment 12. The water enters and leaves the compartment 12 through the openings 13 and 14 which may be provided in any suitable number.

25 The outer wall 15, of the tuyère is preferably provided with a relatively shallow taper whereby the inner end or nose portion of the tuyère will approach the maximum diameter for the opening through which it is introduced in installation. This makes 45 for greater water capacity and provides ample room for adequate covering of refractory material and yet permitting the water chamber to extend practically to the inner end of the tuyère.

50 The water compartment 12 at the inner end is reduced in size by the partition 17 which extends from the outer wall 15 to the inner wall 18 of the tuyère. The wall 17 is arranged as shown and provides with the 55 outer wall portion 19, of the tuyère, compartments 20, for receiving the refractory material 21.

Extending radially between the inner wall 17 and the outer wall 19, are a plurality 60 of radial walls 22, which divide the refractory compartment or space into a plurality of smaller refractory compartments such as is clearly shown in Figure 2. These compartments are of the shape shown in Figure 65 1 and have their outer ends extending

through the outer wall of the tuyère to provide an opening 23, through which the refractory material is introduced.

It is obvious from this construction, that the outer wall 19 covering the refractory material, offers great protection to the refractory material and that any damaging heat at this location is rapidly conveyed inwardly through the walls or webs 22 to the water compartment whereby the water compartment is capable of having a maximum cooling effect for the tuyère. It will also appear that if the outer wall 19 is completely worn away, that the refractory material will still be held in position surrounding and protecting the nose of the tuyère by means of the webs or walls 22.

70 A tuyère in this condition, is still capable of prolonged use and offers all of the advantages of refractory nose tuyères. It will also appear that all of the other objects and advantages pointed out for this invention are accomplished in this construction.

75 It is to be understood that the various changes and modifications are contemplated, all as will fall within the scope of the invention as is pointed out in the appended claims.

I claim:

1. A tuyère of integral metal having in combination, a water compartment and a 95 compartment for refractory material located in the nose thereof, and surrounding a portion of the water compartment and metallic webs extending between the outer wall of said second named compartment and the 100 wall between said water and refractory compartment.

2. A tuyère of integral metal having in combination, a water compartment and a 105 compartment for refractory material located in the nose thereof, said compartments having a wall in common therebetween extending longitudinally of said tuyère and metallic web means extending from said wall to the outside wall of said tuyère.

3. A tuyère of integral metal comprising an annular hollow member, a partition adjacent the nose thereof for dividing said member into a water compartment and a compartment for refractory material, and metallic web members extending from said partition to the outside wall of said tuyère through said compartment for refractory material.

4. A tuyère of integral metal having in 120 combination, a water compartment and space for refractory material, said space comprising a plurality of independent compartments overlying the end and a portion of the sides of said water compartment, each separated 125 from the other by a metallic wall.

5. A tuyère of integral metal having in combination, a water compartment and space for refractory material, said space comprising a plurality of independent compartments 130

overlying the end and a portion of the sides of said water compartment, each separated from the other by a metallic wall and each having a filling opening in the side of the 5 tuyère removed for the nose thereof.

6. A tuyère of integral metal of the character described having a water compartment and a compartment for refractory material, said last named compartment having outer 10 and end wall coverings, and web members of high heat conductivity extending between said outer and end wall coverings and a wall of said water compartment.

Signed at Youngstown, Ohio, this 12th 15 day of July, 1929.

LOUIS M. NESSELBUSH.
